MORRIS SHELDON LORD, OF SCHENECTADY, NEW YORK.

MEANS FOR MARKING OR CUTTING LENSES.

1,117,264.

Specification of Letters Patent. Patented Nov. 17, 1914.

Application filed August 12, 1911. Serial No. 643,777.

To all whom it may concern:

Be it known that I, LEWIS H. SKINNER, a citizen of the United States, residing at Schenectady, county of Schenectady, State 5 of New York, have invented certain new and useful Improvements in Means for Marking or Cutting Lenses, of which the following is a specification.

This invention relates to means for marking or cutting lenses.

The object of the invention is the provision of an instrument operating in a novel and more efficient manner, and also the provision of an instrument of compact and relatively simple construction by which an uncut lens of any kind can be readily placed in any desired angular or axial position, firmly held by its edge in said position, and its finished outline marked or cut by a cutting tool that is guided by a pattern or templet of any desired shape, preferably arranged directly over the lens, while the operator has at all times an unobstructed view of and free access to the lens and the associated mechanism, which greatly facilitates the general operation and also the detection of any tendency of the lens to move away from its proper position, although such tendency is practically eliminated by the invention, thereby insuring a high degree of accuracy in the positioning of the axis of the lens which is so very essential in the preparation of lenses.

In the accompanying drawing illustrating 35 one of the embodiments of the invention, Figure 1 is a top view of the instrument showing the parts in one of the many positions that they take in use; Fig. 2 is a section on the line 2—2 of Fig. 1; Fig. 3 is a 40 longitudinal section of one of the pattern clamps; Fig. 4 is a top view of a lens pattern or templet; and Fig. 5 shows the general outline of an uncut lens.

The uncut lens 6, as it is received from 45 the manufacturer, has its faces ground to definite curvature or form but its periphery or edge is more or less rough and somewhat larger than the finished lens is to be. The axis of this lens, as determined by a suitable 50 instrument, is marked upon its surface before the cutting operation, usually by means of India ink as shown at 7, in Fig. 5. The curvature of the lens 6 shown in Fig. 2 is chosen merely for the purpose of illustra-

tion and can be of any desired form, convex 55 or concave.

The angular and axial positions of the axis of the finished lens are determined by placing the lens 6 over the central portion of a protractor or graduated circular plate 60 8, cut in or mounted upon the lens supporting member or base 9 of the instrument which may be of any suitable form. In the drawing, one form of base is shown which can be provided with a drawer 10 for conveniently holding patterns and other parts. The protractor is divided into degrees by lines preferably extending from its center to its circumference. The number of degrees corresponding to each line is marked 65 on the actual protractor but most of these numbers have been omitted from the drawing for the sake of clearness. After alining the axis of the lens with the proper line of the protractor or decentering it a certain 70 number of millimeters, as may be necessary, it is secured in position by the clamps 11, 12, the recessed inner ends 13, 14, of which are provided with arms or branches having inwardly extending projections 15, 16, that 75 engage the edges of the lens. The outer ends of the clamps are provided with slots 17, 18, through which studs 19, 20, project. The clamps are thus longitudinally and angularly adjustable about their studs or 80 pivots and can be secured in any position to which the operator moves them by means of the clamping nuts 21, 22, on the ends of the studs. The studs are attached to the outer ends of a bar or support 23 arranged 85 below the protractor and pivotally mounted upon a stud or screw 24 having its axis passing through the center of said protractor. The studs 19, 20, project upwardly, from the bar through slots 25, 26, in the top 90 of the base that are concentrically arranged with respect to the axis of the protractor and are of sufficient length to permit the necessary angular adjustment of the studs and lens clamps. Ordinarily these slots 95 will extend over a little more than ninety degrees.

When the lens has been clamped in proper position a pattern or templet of the type shown in Fig. 4 is placed over the lens and 100 secured in place by means of the clamps 27, 28, and the clamping nuts 29, 30, on the studs 31, 32, projecting upward from the

base 9 through said pattern clamps, the clamps being slotted at 33, 34, so that they are longitudinally and angularly adjustable about their studs or pivots. The outer ends 5 of the clamps 27, 28, are bent downwardly to rest on the top of the base. The inner ends are provided with pads of any suitable material that engage the pattern and said ends are held up in convenient position 10 to be slipped over the pattern by springs 42 arranged between the clamps and the base 9.

The pattern or templet 35 is preferably made of transparent celluloid, or other transparent or substantially transparent material, 15 so that when it is in position the operator has an unobstructed view of the lens and the protractor during the marking operation and can detect any disturbance of the position of the lens. He can also see how 20 close the cutter is running to the rough edge of the lens and thus avoid breakage and loss of lenses. The patterns are made sufficiently thick to stand usage without injury and have openings 36 that are elliptical, round or of other forms, corresponding 25 to the finished shape of the lens. The axes of the openings are marked on the patterns at 37, 38, so that these marks can be aligned or made to register with the axes of the protractor when positioning the patterns over 30 the lens. The material of the patterns is so tough and elastic that it will conform more or less to the curvature of the edge portion of the lens when clamped down.

35 Rotatably mounted at one end in a bearing 39, pivotally supported on the base 9, is a jointed arm 40 that carries a diamond or other cutter 41 at its outer end. After the lens and pattern have been secured in position, as above described, the operator brings the cutter into contact with the lens and moves it around the edge of the opening 36, thus making a cut or mark in the surface of the lens at a distance from the 45 edge of the opening equal to the radius of the cutter holder, the dimensions of the opening being made correspondingly larger than those of the finished lens. After the cut or mark has been made, the pattern and 50 lens clamps are released and the lens removed. The portion of the lens outside of the mark or cut is then broken off in the usual manner and the edges of the lens ground smooth. If desired, a manually held 55 and operated cutter can be used with the rest of the instrument instead of the cutter described as will be obvious to those skilled in the art.

In using the instrument, the operator 60 first places the uncut lens over the protractor in the desired position with respect to its graduations and while holding it with one hand, with the other hand brings one of the lens clamps into position to engage 65 the edge of the lens and secures it in place

by screwing down its clamping nut. Then the other clamp is similarly engaged with the opposite portion of the edge of the lens and secured in place. This method of securing the lens by its rough edge has 70 proved to be very effective in practice and obviously is not to be limited in its use to the particular instrument illustrated in the drawing, since it can be used with other forms of pattern and cutting mechanisms. 75 After securing the lens firmly in position, in the manner just described, the pattern is placed over the lens, preferably in direct contact with its upper surface, and after locating its marks or axes in proper position 80 with respect to the protractor, it is held by one hand, while being clamped in position by the other hand.

From the foregoing it will be evident 85 that the lens is firmly held while the operator has at all times an unobstructed view of the lens and protractor, and none of the parts interferes with the free manipulation of the cutter, so that lenses can be accurately and rapidly cut to meet the specifications of an oculist's prescription. 90

In accordance with the provisions of the patent statutes, I have described the principle of my invention, together with the apparatus which I now consider to represent the best embodiment thereof; but I desire to have it understood that the apparatus shown is only illustrative and that the invention can be carried out by other means. 100

What I claim as new and desire to secure by Letters Patent of the United States, is:—

1. In a lens cutter or marker, the combination of a support for the lens which is provided with angular graduations, adjustable clamps, each of which has arms engaging the edge of the lens for holding it with its axis in the desired position relative to said graduations, and a pattern that is placed over the lens and is provided with an opening for determining the shape of the finished lens, the arrangement of the clamps and the pattern permitting free access to the entire surface of the portion of the uncut lens that is to form the finished lens. 110

2. In a lens cutter or marker, the combination of a support for receiving the lens during the cutting or marking operation which is provided with graduations that are visible through the lens, independently slideable devices mounted on the top of the support which engage the edge of the uncut lens and hold it in the desired position on the support relative to the graduations, a pattern that is supported over the lens and has an opening therein, and means engaging the outer portion of the pattern for holding it in place on the lens thereby leaving the central portion exposed. 120

3. In a lens cutter or marker, the combina- 130

tion of a support for the lens during the cutting or marking operation that is provided with a protractor that is visible through the lens, a pivotal member located below the lens, studs carried by the member, devices adjustably mounted on the studs that are in sliding engagement with the top of the support and engage and hold the lens thereon with its axis in any desired relation to the protractor, and means for securing the devices in adjusted position.

4. In a lens cutter or marker, the combination of a support for the lens that is provided with graduations, pivots, a support for the pivots that is rotatably mounted on the first support, clamping devices adjustably mounted on the pivots that engage the lens and hold it on its support in any desired relation to the graduations, and means for securing the devices in their adjusted positions.

5. In a lens cutter or marker, the combination of means for supporting the lens that is provided with a graduated circle, a support, a pivot on which the support is mounted for movement about the center of the circle, studs or pivots carried by the outer ends of the support, clamping devices adjustably mounted on the studs that engage the edge of the lens, and means for securing the devices in their adjusted positions.

6. In a lens cutter or marker, the combination of a lens supporting member having a graduated circle for positioning the lens, a support, a pivot on which the support is mounted for movement about the center of the circle, studs carried by the outer ends of the support, clamping devices having slots that engage the studs and are angularly and longitudinally adjustable about said studs, and nuts on the studs for securing the devices and studs in their adjusted positions.

7. In a lens cutter or marker, the combination of a base having a graduated circle on its upper portion for positioning the axis of the lens, a bar arranged below said portion, a pivot in line with the center of the circle on which the bar is mounted, studs carried by the ends of the bar that project upwardly above said portion and are movable with the bar about the center of the circle, clamping devices having slots in their outer ends that engage the studs above said portion and are angularly and longitudinally adjustable about said studs, the inner ends of the devices being adapted to engage the lens, and nuts on the studs for securing the studs and devices in adjusted position.

8. In a lens cutter or marker, the combination of a support having a graduated circle on its top and concentric slots adjacent the edge of the circle, a bar arranged below the top of the support, a pivot in line with the center of the circle on which the middle of the bar is mounted, studs carried

by the ends of the bar that project upwardly through said slots and are movable with the bar about the center of the circle, clamping members having slots in their outer ends that engage the projecting portions of the studs and are angularly and longitudinally adjustable about said studs, the inner ends of the clamping members engaging the edge of the lens, and nuts on the upper ends of the studs for securing the bar and devices in their adjusted positions.

9. In a lens cutter or marker, the combination of a support for the lens, and means for holding the lens on the support, comprising clamping members having recessed ends that engage the edge of the lens.

10. In a lens cutter or marker, the combination of a support for the lens, and means for holding the lens on the support, comprising clamping members having recessed inner ends provided with projections that engage the edge of the lens.

11. In a lens cutter or marker, the combination of a support for the lens, and means for holding the lens on the support, comprising clamping members having forked ends provided with inwardly extending projections that engage the edge of the lens.

12. In a lens cutter or marker, the combination of a support for the lens, and means for holding the lens on the support, comprising adjustable clamping members having slotted outer ends and recessed inner ends, and devices that engage the slotted ends and hold said members in adjusted position.

13. In a lens cutter or marker, the combination of a support for the lens, and means for holding the lens on the support, comprising adjustable clamping members having slotted outer ends and forked inner ends, pivots on the support that enter the slots and permit said members to be angularly and longitudinally adjusted about the pivots, and means for securing the members in adjusted position.

14. In a lens cutter or marker, the combination of a fixed support for the lens during the cutting or marking operation, clamping means for holding the lens in position on the support, a pattern of substantially transparent flexible material that rests on the lens, and means carried by the support and extending over the outer portion only of the pattern for holding it in place on the lens.

15. In a lens cutter or marker, the combination of a fixed support for the lens during the cutting or marking operation, clamps that engage the lens on opposite sides and hold it in position on the support, a lens pattern of substantially transparent flexible material having an opening of similar shape to the outline of the finished lens and having the axes of the opening marked on it, said pattern resting on the lens, and individual

means carried by the support and resting on the top of the pattern near its outer edges for holding the same in position on the lens.

16. In a lens cutter or marker, the combination of a support for the uncut lens that is provided with graduations, universally adjustable clamps that engage the edge of the uncut lens on opposite sides and hold it in position on the support, a templet that is placed on top of the lens and has a centrally arranged opening that is similar in outline to the finished lens, the axes of the opening being indicated on the templet, and clamps that rest on the support and templet for holding the latter in position relative to the lens and graduations.

17. In a lens cutter or marker, the combination of a support for the uncut lens that is provided with graduations, means that engage the edge of the uncut lens on opposite sides at a plurality of points and hold it in position on the support, a transparent templet that is placed on top of the lens and has an opening in its middle portion that is similar in its outline to that of the finished lens, the axes of the opening being marked on the templet, a pivotally supported member located below the lens support, studs or pivots mounted on the member, clamps for the templet that are provided with slots, studs arranged to enter the slots, and nuts on the studs for holding the clamps and templet in position.

18. In a lens cutter or marker, the combination of means for supporting an uncut lens during the cutting or marking operation, means that is slidably mounted on top of the supporting means and engages the edge of the lens for securing it in position on said supporting means, a lens pattern that is placed over the lens, and a jointed cutter carrying arm that is pivotally mounted on said supporting means.

19. In a lens cutter or marker, the combination of means for supporting an uncut

lens, means that engages the edge of said lens and holds it in position on the supporting means, a templet that is placed over the lens and has an opening that is similar in shape to the outline of the finished lens, means for securing the templet in position, a jointed cutter-carrying arm, a pivot for the arm, and a support for the pivot that is pivotally mounted on the supporting means.

20. In a lens cutter or marker, the combination of a support for the lens, studs, a common support for the studs that is movably mounted on the first support, and clamping devices mounted on the studs that engage the lens and hold it on its support.

21. In a lens cutter or marker, the combination of a support for the lens, clamping devices that engage the lens and hold it on the support, and a common support for the clamping devices that is movably mounted on the first support.

22. In a lens cutter or marker, the combination of a support for the lens, means for holding the lens on the support comprising members whose ends engage the periphery of the uncut lens and are arranged in substantially the same plane with said periphery, a pattern that is placed over the lens, said pattern having an opening that is similar in shape to the finished outline of the lens, and means that engages the outer portion of the pattern and holds it in place.

23. In a lens cutter or marker, the combination of a support for the lens during the cutting or marking operation, holding means that engages the edge of the lens and holds it on the support, and a support for the holding means that is rotatably mounted on the first support.

In witness whereof, I have hereunto set my hand, this tenth day of August, 1911.

LEWIS H. SKINNER.
